(73) Assignee: **EHWA Diamond Ind. Co. Ltd.**, Kyongki-do (KR)

(57) CLAIM

(**) Term: **14 Years**

The ornamental design for a saw blade for cutting steel-reinforced structure, as shown and described.

(21) Appl. No.: **29/128,295**

DESCRIPTION

(22) Filed: **Aug. 22, 2000**

FIG. 1 is a perspective view of a saw blade of the present invention looking toward the top and left side;

(51) LOC (7) Cl. **15-09**

FIG. 2 is a front view of the saw blade;

(52) U.S. Cl. **D15/139; D8/70**

FIG. 3 is a rear view of the saw blade;

(58) Field of Search D15/139; D8/70; 83/663, 666, 676, 349, 502, 508.3, 675

FIG. 4 is an elevation view of the left side; the right side is substantially a mirror image of the left side;

(56) References Cited

FIG. 5 is a bottom plan view; and,
